DESIGN FOR AN AUTOMOBILE

George Lim Chieng, New York, N. Y.

Application January 6, 1942, Serial No. 105,041

Term of patent 14 years

To all whom it may concern:

Be it known that I, George Lim Chieng, a citizen of the United States, residing at New York city, county of New York, and State of New York, have invented a new, original, and ornamental Design for an Automobile, of which the following is a specification, reference being had to the accompanying drawing, forming a part thereof, wherein:

Both sides of the design are similar.

I claim:

The ornamental design for an automobile, as shown and described.

GEORGE LIM CHIENG.
